LOCKING DEVICE FOR DOUBLE-BARREL FIREARMS

Fritz Zehner and Hans Zehner, Suhl, Germany,
assignors to the firm J. P. Sauer & Sohn,
Gewehr-Fabrik, Suhl, Germany

Application November 24, 1937, Serial No. 176,338
In Germany December 5, 1936

6 Claims. (Cl. 42—42)

This invention relates to locking devices for double-barrel firearms and has particularly for its object to prevent double firing of firearms of this kind by an involuntary second pulling of the trigger which had already been pulled for firing the one barrel and likewise by an involuntary pulling of the second trigger.

In order to attain this, according to our invention we propose to equip the said trigger system with a locking device including one or more locking members which by action of their inertia presented against the recoil taking place on firing will first move into the path of the retractive motion of the pulled trigger and thereupon temporarily into the path of said trigger subsequent to retraction, and also lock the second trigger during the entire motion of said locking member or members.

In the drawings we have shown as an exemplification two forms of locking devices constructed according to this invention to be used in connection with double-barrel firearms.

Our novel locking device in combination with the trigger system for double-barrel firearms is described herein below and shown in the accompanying drawings in two forms of construction, which naturally may also be used in connection with trigger systems of a type other than that described herein and shown in the drawings.

In the drawings which form part of this specification, Fig. 1 is a diagrammatic side-view, partly in section, showing a trigger system equipped with one form of construction of our present locking device in operative position,

Fig. 2 a partial top-view of Fig. 1,

Fig. 3 a side-view, similar to Fig. 1, showing the same trigger system and locking device, both in a position after having pulled one trigger, that is in condition of firing,

Fig. 4 a further side-view, similar to Fig. 1, showing the trigger system together with the locking device in still another position different from those shown in Figs. 1 and 3,

Fig. 5 a detail-view of our novel locking device at an angle perpendicular to Figs. 1 and 2, and

Fig. 6 a side-view, partly in section, showing a trigger system and a second form of construction of our present locking device co-operating with said system.

In order to more clearly describe our present invention we regard it proper, prior to describing the locking device, to more clearly illustrate the aforesaid trigger system which is equipped with a locking device according to our invention.

Referring more particularly to the drawings,

on the strap 1 which forms the base for the breech of the double-barrel firearm there are mounted two triggers 2 and 3 each having a plate-shaped extension or trigger-blade 5 and 6 swingable about a common pivot 4, while a coupling rod 7 is positioned intermediate said trigger-blades. The coupling rod 7 is pivoted at its front end as shown at 8 to a lever 9 mounted to rock about a pivot 10. At its rear end the coupling rod 7 is provided with two oppositely disposed lateral extensions 11 and 12, said extensions serving to engage with recesses 13 provided in each of the trigger-blades 5 and 6.

Above the coupling rod 7 there is mounted 15 swingably about the pivot 4 a further lever 14 extending with its beak 15 as far as to a catch 16 on the coupling rod 7, said lever keeping the latter fixed in the position shown in Fig. 1. A coiled spring 17 serves to draw the coupling rod 20 7 towards the front by the aid of said lever 9 and, in addition, to keep said lever 14 depressed by the aid of a further lever 18, all as shown on the left-hand end of Figs. 1, 3 and 4.

On each trigger-blade 5 and 6 there is provided 25 a threaded bolt 19 positioned underneath said lever 14 and adapted to engage with a notch provided in the lower face. Upon pulling one of the two triggers 2 or 3 and the consequent upward rocking of the corresponding trigger-blade 30 5 or 6 the beak 15 of lever 14 will likewise be rocked upward by means of said bolt 19, the coupling rod 7 now being released and pulled towards the front by action of the coiled spring 17, until said rod abuts with one of its lateral 35 extensions 11 and 12 against the trigger-blade which is in raised position, as shown in Fig. 3. In the position of the trigger-blades 5 and 6 as shown in Fig. 3, the firearm is in condition of firing the first barrel.

Upon releasing the trigger 2 which had first been pulled, the latter will return into its initial position so that the recess 13 of the respective trigger-blade 5 will again be positioned at the height of the lateral extension 11 on the coupling rod 7. This rod consequently will be drawn by the pressure spring 17 on the lever 9 still further towards the front, with the result that now the lateral extensions 11 and 12 on the coupling rod 7 will engage with the recess 13 of both trigger blades 5 and 6, so that these and therewith both triggers 2 and 3 will now be coupled with each other as represented in Fig. 4. Upon repeated pulling of the same trigger 2 now also the trigger-blade 6 appertaining to the other trigger 3 will be rocked upward so that now the

second barrel may be fired. Evidently the second barrel may likewise be fired by pulling said other trigger 3. If, on the other hand, the trigger 3 is pulled to fire the first barrel, the procedure is opposite to that which had above been described, that is after firing the trigger 3 will be coupled with the trigger 2.

Upon opening the breech of the firearm, the coupling rod 7 is again moved into its initial position shown in Fig. 1 by means of an extension not shown provided on the breech slide.

Now, in order to prevent an involuntary or accidental second pulling of the trigger which has just been used to fire the first barrel, according to our invention we provide a specially constructed double-acting locking device for the trigger system.

At first we will describe the locking device which forms part of the construction shown in Figs. 1-5. Interiorly of the strap 1 there is mounted a locking member 21 rockable about a pivot 22. On firing, the locking member 21 will be rocked by action of its inertia against the recoil of the firearm first in direction of the arrow 23a, while immediately thereupon it is again rocked in opposite position, as indicated by the arrow 23, likewise by action of its inertia.

In order to assist the rocking motion of the locking member 21 in direction of the arrow 23a, this motion being caused by the inertia of the locking member acting in direction against the recoil due to firing, said locking member 21 is resiliently coupled with a weighted lever 24 whose rocking motion towards the left is prevented by the integral lug 25 which abuts against the strap 1. Resiliency between the locking member 21 and the weighted lever 24 is due to a tension spring 26 interposed between these two. The locking member 21 and the weighted lever 24 are provided with a recess 27 therebetween as shown in Fig. 5, the extensions 28 on both trigger-blades 5 and 6 protruding into said recess. Furthermore, said locking member 21 is provided with a pin 29 extending above both trigger-blades 5 and 6, said pin 29 co-operating in accordance with the temporary position of the locking member 21 each with a slot 30 provided in either blade 5 and 6 or with the curved upper edge 31 of the extension 28 of said blades. The slot 30 more particularly is composed of two portions 32 and 33, the former extending from said curved edge 31 nearly but not quite coaxial with pivot 4 for the trigger-blades 5 and 6 while the latter portion 33 adjoining the former is coaxial with pivot 22 for the locking member 21.

The locking device so far described operates as follows: Upon pulling one of the two triggers 2 or 3, the locking member 21 will be rocked thereby a small distance against the tension of the spring 26 towards the front, the pin 29 entering the portion 32 of the slot 30. The pin 29 now will be positioned above the tongue 34 (Fig. 3) of the trigger-blade which is in position of rest and will effect locking of the latter. On firing, the locking member 21 will move by action of its inertia against the recoil in direction of the arrow 23a, while the pin 29 moves in the portion 33 of the slot 30 towards the front until it is stopped at the end of this slot as shown in Fig. 3. During rocking motion of the locking member 21 due to the recoil on firing and during the subsequent backward rocking due to the tension of the spring 26, this backward rocking continuing until said locking member 21 has arrived in its initial position, the trigger which had been pulled to fire the first

barrel will be locked against returning into position ready for firing. The other trigger at present in position of rest will now likewise be locked against accidental pulling, the pin 29 abutting against the edge 31 of the extension 28 of the trigger-blade which is temporarily in condition of rest.

After the recoil of the firearm has come to a stop at the shoulder of the marksman, the weighted lever 24 by action of its inertia will be rocked in clockwise sense (Fig. 4) against the pull of the spring 26 and against the pressure of the spring 35. Immediately upon returning of the trigger which had been pulled into position ready for firing, the locking member 21 together with the pin 29 thereon will be drawn by the spring 26 above the rear portion of the curved edge 31 of the extensions 28 of the trigger-blades and move along a circle drawn round the pivot 22 for the locking member 21. In this manner, locking of both trigger blades is accomplished as represented in Fig. 4. A second pulling of a trigger to fire a second time is made possible only after the locking member 21 and the weighted lever 24 have returned into their initial position represented in Fig. 1 and after the coupling has taken place in the meanwhile between the two triggers.

In the form of construction of the locking device so far described there is provided for both triggers only a single locking member 21 and a single weighted lever 24.

Evidently also constructions of our new locking device are possible in which a locking member 21 and a weighted lever 24 are provided for each trigger. There are, furthermore, constructions possible in which a special weighted lever 24 is dispensed with.

Our new locking device may furthermore be constructed in such a manner that the locking member 21 and the weighted lever 24 are each provided with a locking pin 29. In this case the locking member 21 may be so arranged that it is held against being rocked from the position indicated in Fig. 1 towards the right, in a way that the respective rocking motion will be imparted only to the weighted lever 24 to temporarily move into the path of the retractive motion of the trigger and to effect locking by the pin 29.

In Fig. 6 we have shown a modified construction of our present locking device in which the aforesaid locking member 21 and the weighted lever 24 which are rockable round a common pivot are replaced by a pair of parallel locking slides 36 and 37. In the present case the longitudinally displaceable slide 35 is mounted in a frame-like extension 38 of the strap 1 and provided with a bore or recess 39, the nose 40 of the trigger-blade 41 being positioned underneath said recess. Said slide 36 is pressed towards the front by means of a coiled spring 42 and abuts against a stop 43 on the aforesaid extension 38. Upon pulling the trigger, the nose 40 of the trigger-blade 41 will move into the bore or recess 39 on the slide 36, as indicated by the full-drawn position of the trigger and blade 41.

During the recoil due to firing, said second slide or bolt 37 which is mounted within the rear part of the outer slide 36 will be moved towards the front and caused to engage with a bore 44 at the rear end of the trigger-blade 41, this preventing the trigger from prematurely returning into position for firing. On the other hand, the trigger may be free to return into this latter

position after the slide 37 has been pushed back by action of the spring 42. During this returning motion of the trigger, the slide 36 will be given a backward motion due to its inertia presented against the stopping of the recoil at the shoulder of the marksman which had taken place in the meanwhile. The trigger will thus be locked against a second involuntary or accidental pulling, the slide 36 being at this time in a position as indicated by the dash-dotted line.

In the form of construction of the locking device shown in Fig. 6 there may be provided for each trigger an outer slide 36 and an inner slide or bolt 37. However, it will also be possible to provide a single outer slide 36 common to both triggers, while for each trigger an inner slide or bolt 37 must be present within the common slide 36.

We claim:

1. A locking device for preventing double firing of double-barreled firearms with two triggers including in combination, an extension plate on each trigger, said plates being pivoted in substantially parallel planes for lifting as a result of the pull of their respective triggers, a locking member mounted to be moved by inertia against recoil during firing, said plates and locking member being provided with cooperating means so shaped and positioned that movement of recoil of the firearm moves the locking member means into the return path of the plate means of the pulled trigger, and additional means aiding the reverse movement of said locking member on counter-recoil to position said cooperating means to then interlock and hold the now retracted trigger plate against trigger pull for a period.

2. A locking device as specified in claim 1, in which the locking member is also provided with means cooperating with the plate of the unpulled trigger to lock it during the entire motion of the member.

3. A locking device as specified by claim 1, including identical trigger-blades, each of which is provided with a slot and with a curved edge on each side of said slot, a pin carried by said locking member and extending over both of said trigger-blades and normally over the slot entrances, said pin adapted to be received, upon motion of one of said trigger-blades into firing position, within said slot therein, said slot being shaped to move said pin to bear against said curved edge on the other of said trigger-blades to prevent a firing thereof until said locking member has again returned into initial position.

4. A locking device as specified by claim 1, including identical trigger-blades, each of which is provided with a slot and with a curved edge on each side of said slot, a pin carried by said

locking member and extending over both of said trigger-blades and normally over the slot entrances, said pin adapted to be received, upon motion of one of said trigger-blades into firing position, within said slot therein, and to bear against said curved edge of the other of said trigger-blades to prevent a second firing until said locking member has again returned into initial position, said slots comprising an outer portion extending essentially in the direction of motion of said trigger-blades and a further inner portion adjoining the former portion and following a circle drawn about the pivot for said locking member, while said edges on said trigger-blades follow another circle drawn about said pivot.

5. A locking device for preventing double firing of double-barreled firearms with two triggers including in combination, an extension plate on each trigger, said plates being identical and coaxially pivoted in substantially parallel planes for lifting as a result of the pull of their respective triggers, a locking member mounted to be moved by inertia against recoil during firing to cooperate with either of said plates, said plates and locking member being provided with means whereby the first movement of recoil of said member moves its means into the return path of the plate means of the pulled trigger, said means being constructed to interengage and lock the same trigger plate after retraction against trigger pull for a period initiated by the counter-recoil, said locking member constituting a weighted body pivoted to rock about a fixed axis.

6. A locking device for preventing double firing of double-barreled firearms with two triggers including in combination, an extension plate on each trigger, said plates being identical and coaxially pivoted in substantially parallel planes for lifting as a result of the pull of their respective triggers, a locking member mounted to be moved by inertia against recoil during firing to cooperate with either of said plates, said plates and locking member being provided with means whereby the first movement of recoil of said member moves its means into the return path of the plate means of the pulled trigger, said means being constructed to interengage and lock the same trigger plate after retraction against trigger pull for a period initiated by the counter-recoil, said locking member constituting a weighted body pivoted to rock about a fixed axis, a second weighted body pivoted coaxially with the first, and means whereby the masses of the two bodies are additive in effect on counter-recoil only.
